[57] **CLAIM**

The ornamental design for a flashlight clip for helmet, as shown and described.

DESCRIPTION

FIG. 1 is a perspective view of a flashlight clip for helmet showing my new design;

FIG. 2 is a top view thereof on an enlarged scale;

FIG. 3 is a bottom view thereof on an enlarged scale;

FIG. 4 is a right side view thereof on an enlarged scale;

FIG. 5 is a rear view thereof on an enlarged scale;

FIG. 6 is a left side view thereof on an enlarged scale; and,

FIG. 7 is a front view thereof on an enlarged scale.

The broken lines are shown for illustrative purposes only and form no part of the claimed design.
